United States Patent Office.

CHARLES H. ELLIOTT, OF YORK, PENNSYLVANIA.

Letters Patent No. 77,431, dated April 28, 1868.

IMPROVEMENT IN CHURNS.

The Schedule referred to in these Letters Patent and making part of the same.

TO ALL WHOM IT MAY CONCERN:

Be it known that I, CHARLES H. ELLIOTT, of York, in the county of York, and State of Pennsylvania, have invented a new and improved Churn; and I do hereby declare that the following is a full, clear, and exact description thereof, reference being had to the accompanying drawings, making a part of this specification, in which—

Figure 1 is a perspective view of the improved machine complete.

Figure 2 is a longitudinal section taken in a vertical plane through the centre of the machine.

Figure 3 is a transverse section taken through the centre of the machine.

Figure 4 is a side view of the dasher, detached from the machine.

Similar letters of reference indicate corresponding parts in the several figures.

This invention relates to certain new and useful improvements on that class of power-churns wherein the dasher receives a rotary motion about its axis, and, at the same time, a vertical reciprocating motion.

The nature of the first part of my invention consists in communicating a vertical or rectilinear reciprocating motion to a churn-dasher, at the same time giving to this dasher intermittent right and left rotary motions about its axis, by means of a vertically-reciprocating dash, which is guided in a stationary frame, and a spirally-grooved dasher-shaft, into the grooves of which teeth engage, which are applied to a stationary cross-head, as will be hereinafter explained.

The second part of my invention consists in applying to the dash-rod a suitable perforated disk, and a number of radial arms, carrying fixed and rotating wings, which wings are designed to serve in conjunction with the disk to break up the butter-globules to the best advantage, and with the greatest possible facility, as will be hereinafter explained.

The invention further consists in providing a churning-machine, of the construction hereinafter set forth, with means whereby the vessel for containing the cream can be readily removed from and applied to the frame and working parts of the machine; said means consisting of a removable cross-head, arranged over the said vessel, and a depression on the bed of the machine, for receiving and centring this vessel and keeping it steadily in place, as will be hereinafter explained.

To enable others skilled in the art to understand my invention, I will describe its construction and operation.

In the accompanying drawings, A represents the horizontal bed of the machine, which may be constructed as shown in the drawings, or in any other suitable manner which will afford a substantial foundation for supporting the churn-vessel, and the several parts used for moving the dasher. Upon this bed are uprights, B B, which are connected together by horizontal pieces, B', at their upper ends; so as to form a strong rectangular frame, for receiving and serving as a guide for a vertically-reciprocating sash, C. This sash moves up and down between, and is kept in place laterally by means of upright strips, a a and D D, which are applied to the frame-uprights B B, substantially as shown in fig. 1, so as to form recesses, in which the vertical legs of the sash C slide. The lower extremities of the sash are connected, by means of rods b b, with the wrist-pins of crank-arms c c, which arms are keyed upon the extremities of a shaft, E. This shaft E is located beneath the top of the bed A, and is supported in bearings e e. It carries upon it, near one end, a grooved pulley, F, over which a belt, d, passes, which also passes over a large circumferentially-grooved driving-wheel, G. This driving-wheel is applied upon a short shaft which has its bearings upon the upper end of an inclined post, H, and by means of a crank handle, I, shown in fig. 1, said wheel G can be conveniently rotated, and motion imparted to the shaft E and sash C.

Instead of the wheels F G, any other suitable means may be adopted for giving motion to the crank-shaft, and, if desirable, provision may be made for driving the churn-movement by animal or other convenient motive-power.

On top of the upright inside pieces D, and secured to these pieces by hooks, S, or other convenient fastening, is a horizontal head-piece, D', the extremities of which are notched, so as to embrace the upright strips a a, thereby preventing it from slipping out of place laterally. Through the middle of the length of this head-piece

D' is a notch, V , through which a spirally-grooved portion, f , of the dash-shaft N plays. On top of this head-piece, and screwed thereto by thumb-screws, $J' J'$, are two adjustable plates, J , carrying on their ends, nearest the grooved portion f , oblique teeth, $e e$, which enter the spiral grooves f' on opposite sides of the portion f , and thereby cause the dash-shaft to rotate in one direction when it is elevated, and in an opposite direction when this shaft is depressed. The thumb-screws pass through oblong slots made through the extremities of the plates $J J$, so that by loosening these thumb-screws, the plates can be moved back, and the teeth $e e$ retracted from their spiral grooves.

The upper end of the dash-shaft terminates in a reduced cylindrical portion, t' , having an annular groove made in it, which portion enters a hole made through the centre of the horizontal cross-head of the sash C , and receives through its groove a transverse key, t . This key attaches the upper end of the dash-shaft to the sash, and allows the dash-shaft to rotate freely about its axis.

The dash-shaft N passes down vertically through the centre of a circular cover, K , which is fitted upon a cylindrical churn-vessel, K' , shown in figs. 1, 2, and 3, and upon the lower end of this shaft is a circular perforated disk or dasher, P , which serves, in conjunction with several radial wings upon the dash-rod, to produce butter very rapidly.

The vessel K' is fitted into an annular recess, formed by the ring-base L , which latter is secured down fast upon the base, A , as shown in the drawings. The base-ring is sufficiently high to form a receptacle, which will centre and keep in place the vessel K' , and allow this vessel to be removed from the machine at pleasure, when the head-piece D' and key t are detached.

The radial wings, $g g$ and $h h$, are perforated and secured to short arms, which radiate from the dash-shaft N , as shown clearly in figs. 1 and 4. The radial wings j are secured to tubes, and applied upon arms $i i$, which radiate from the dash-shaft, so that the wings j are allowed to rotate by the resistance of the cream impinging upon them. These wings, together with the perforated dasher P , will cause violent agitation of the milk or cream in the vessel K' when the sash C is reciprocated, and produce the butter in a very short space of time.

It will be seen that the wings are brought into action by the vertical as well as the rotary motion of the dash-shaft, while the dasher P operates only by the vertical motion of said shaft. When shaft E is rotated, the sash C and dash-rod N receive a vertical reciprocating motion. At the same time, the teeth $e e$, engaging with the spiral grooves, f' , upon the enlargement, f , of the dash-rod, cause this rod to receive right and left rotary motions about its axis.

The rectangular sash C , working in guides, formed as shown and described, will give a steady motion to the dash-rod, and keep it in place during its up-and-down movements.

The teeth $e e$ serve not only to give rotary motion to the dash-rod, but they also serve to steady and centre it in its vertical movements.

The head-piece D' serves as a support for the plates J , and also as a brace to the frame of the machine. This piece is detached from its uprights $D D$, and raised a short distance, when it is desired to remove the vessel K' from its seat in the base-ring L .

Having described my invention, what I claim as new, and desire to secure by Letters Patent, is—

1. Communicating a vertical reciprocating motion to the dash-rod N , at the same time giving to this rod right and left rotary motions, by means of a vertically-moving sash, C , a spirally-grooved portion, f , and fixed but adjustable teeth $e e$, arranged and applied within a frame, and driven from a shaft, E , substantially as described.
2. The movable head-piece D' , arranged over the churn-vessel, and provided with adjustable toothed plates $J J$, in combination with sash C and a spirally-grooved portion, f , on the dash-rod, substantially as described.
3. The churn-vessel K' , seated into a fixed base-ring, L , in combination with the movable head-piece D' , and the means, substantially as described, for operating the dash-rod.
4. The perforated dasher P , and dash-rod N , provided with perforated or imperforated radial wings, g or h , constructed and applied substantially as described.
5. The rotary wings j , applied to rods i , projecting radially from the dash-rod, substantially as described.

CHARLES H. ELLIOTT.
